MAX J. SINDLER AND JOSEPH SCHLOSS, OF BALTIMORE, MARYLAND.

SAFETY ATTACHMENT FOR GAS STOVES.

Application filed January 13, 1922. Serial No. 529,009.

To all whom it may concern:

Be it known that we, MAX J. SINDLER and JOSEPH SCHLOSS, citizens of the United States, residing at Baltimore, in the county 5 of Baltimore City and State of Maryland, have invented new and useful Improvements in Safety Attachments for Gas Stoves, of which the following is a specification.

Our present invention has reference to a 10 safety appliance for gas stoves, ranges and burners.

Our object is to produce a simple, cheap and effective means for locking the cocks that control the passage of gas to the several burners of the stove so that none of the said cocks can be accidentally turned on, the locking means being of a nature, however, to permit of the cocks being independently turned to shut off the flow of gas.

20 A further object is to produce a safety appliance for gas stoves or ranges in which all of the cocks controlling the passage of gas to the separate burners are locked from turning to an open position, and wherein 25 the locking means is concealed so that the same cannot be tampered with, wherein an element must be actuated before any of the cocks can be turned on, and also wherein any of the cocks may be operated to close 30 the gas passage controlled thereby.

It is a still further object to produce a safety device for gas stoves in which the casings for the cocks that control the gas passage to the several burners have either 35 integrally formed therewith or effectively secured thereon housings that have arranged therethrough spring influenced members which carry on their outer ends cam elements in the nature of latches to engage the 40 stop pins on the cores of the cocks to hold the said cocks against turning to permit of the flow of gas from the manifold to the several burners, all of said spring influenced members being connected to a bar provided 45 with an operating element or handle preferably in the nature of a yoke member that surrounds the gas conductor pipe leading to the pilot; the said bar may, if desired, be spring influenced to more effectively retain the catch members in contacting engagement with the pins, the said catch members and pins being suitably encased or housed to prevent accidental or mischievous operation of any of the locking means, it

being necessary to exert a pressure against 55 the handle of the bar to move the said bar downwardly to bring all of the latching elements out of engagement with all of the pins on the cores of the cocks to permit of the turning of any of the cocks to allow a 60 flow of gas to any or to all of the burners, while any of said cocks may be independently operated to close the gas passage.

A further object is to produce a means for effectively locking the cocks of a gas 65 stove from turning which may be applied to any ordinary construction of gas stoves.

A still further object is to produce a safety appliance for gas stoves which shall be of a simple construction, cheaply manufactured and marketed, readily applied and which will perform the functions for which it is devised with ease and with accuracy.

The foregoing, and other objects which will appear as the nature of the invention 75 is better understood, may be accomplished by a construction, combination and operative association of parts such as is disclosed by the drawing which accompanies and which forms part of this specification. 80

In the drawing:—

Figure 1 is a top plan view of the gas manifold, cocks, and pilot burner of a gas stove, and illustrating the application of the improvement.

85

Figure 2 is an elevation thereof.

Figure 3 is a greatly enlarged sectional view approximately on the line 3—3 of Figure 2.

85

Figure 4 is a detail enlarged sectional view 90 approximately on the line 4—4 of Figure 1.

Figure 5 is a side elevation of one of the locks.

Figure 6 is a top plan view thereof.

Figure 7 is a perspective view of one of 95 the protector housings or casings for the locks.

Figure 8 is a view looking toward the open face of the shell carrying casing for the shank of the lock, when the lock casing is 100 formed separately from the cock casing.

It will be seen, from an inspection of the accompanying drawings, that we have constructed the casings for the shanks of the 105 slideable locks separate from the casings of the cocks and also that the housing or protector member for the cam heads of the locks are likewise separable members, but we wish

it to be understood before proceeding with a detailed description of the improvement that these elements may be integrally formed with the cock casings.

5 Referring now to the drawings in detail, the numeral 1 designates the gas manifold for any ordinary construction of gas burning stoves. The passage from the manifold to the several burners of the stove are controlled by 10 cocks 2. The cores of the cocks pass through the usual casings 3, the casings, at their upper portions being notched in the usual manner to receive therein the pins 4 which are let in the cores of the cocks and 15 which pins, contacting with the opposed walls of the notches limit the turning of the cores and for sustaining the same in position to open or close the passages. Also connected to the manifold there is the pipe 5 to 20 which the pilot 6 is secured. As is usual, the pilot is at all times lighted.

In the illustrated embodiment, we arrange on each of the valve or cock bodies a shell 7. The shell is in the nature of a semi-circular member, being rounded upon itself to provide an interior which conforms to the exterior of one side of the cock casing, the said shell having its edges provided with spaced outstanding fingers 8 disposed over the pipes 30 or nipples which are in a line with the passage through the valve or cock body. Around the said nipples and contacting with the fingers there are split rings 9, the ends of the said rings being extended to provide 35 parallel members, and through these members there are passed binding means, such as nuts and bolts which compress the said split rings and hold the shells 7 on the cock or valve bodies.

40 Each shell 7 has its outer face centrally formed with a substantially rectangular housing 10 that receives therethrough the substantially rectangular shank 11 of the locking members 12. Each locking member 45 12 has the upper end of its shank 11 provided with an arcuate cam head 13 that terminates in a straight shoulder 14 which is arranged directly over the shank 11. Each shank 11 has a reduced threaded extension 50 15 which passes through the open end of the housing 10 and which also passes through openings in a plate or bar 16. The threaded ends of the extensions 15 are engaged by nuts 17 which bind against the under face 55 of the bar 16. Of course, other means may be provided for securing the locks to the bars. The cam heads 13 of the respective locks 12 have their upper angle faces in the path of contact with the stop pins 4 on the 60 cores of the respective cocks 2, and each of the cocks is provided with a suitable operating handle 18. The reduced portions 15 of the shanks 11 of the locks 12 are surrounded by coiled springs 19 which exert a pressure 65 between the bar 16 and the shoulder at the

juncture of the shank 11 with its extension 15 and whereby the headed ends 13 of the locks are forced into frictional contact with the stop pins 4.

To effectively conceal the locking means, 70 just described, we arrange over each shell 7 and each housing 10 on said shell a casing 20. Each casing is preferably in the nature of a semi-tubular member, the same having its side edges, at a distance from its closed 75 top 21 reduced, and the lower edges of the said reduced portions formed with bendable fingers 22 that pass through slots 23 in the respective shells 7, the said fingers 22 being bent inwardly against the shells. 80

Secured to the bar, at the center thereof there is a substantially yoke-shaped member 24, the said yoke straddling the pipe 5 of the pilot 6. Between the upper or connecting element for the arms of the yoke and the pipe 5 there may be and preferably is suitable guide means 25, and also, if desired, there may be arranged in the yoke between the pipe 5 and the bar 16 a spring 26 which will assist the springs 19 in holding the arcuate cam heads 13 of the locks 12 in positive engagement with the stop pins 4 on the cores of the cocks. The yoke 24 is really in the nature of an operating handle for the bar and may be either secured to the bar, as disclosed by the drawings, or cast therewith. 90

When the cocks are moved to close the passages between the manifold and burners, the stop pins 4 and the cores of the cocks will be in contact with the shoulders 14 on 100 the heads of the locks. The result is that none of the cocks can be turned, and to accomplish this, a downward pressure can be exerted on the U-shaped member or handle 24 of the bar 16. Such pressure will move 105 all of the locks downwardly to bring the shoulders 14 away from the pins 4, so that any of the cocks may be independently turned. Because of the upper angle formation of the arcuate heads 13 of the locks 12, 110 the pins 4 never ride off of the heads, and as a consequence any of the cocks may be turned to closed position independent of such turning of the remaining cocks. The yoke-shaped handle of the bar is directly in 115 contact with the spring influenced valve 30 that admits a sufficient amount of gas to the pilot to retain the same lighted, and when the said bar is moved downwardly, the valve will be fully opened so that a larger flame 120 will be given out from the pilot sufficient to light all of the burners.

It is thought that the foregoing description, when taken in connection with the drawing will fully set forth the construction, 125 operation and advantages of the improvement to those skilled in the art to which such inventions relate without further detailed description, it being thought merely necessary to state that the nature of the invention 130

is such as to render the same susceptible to changes in form, proportion and other details of construction than that herein set forth, and it is therefore to be understood 5 that we are entitled to all such changes and modifications as fall within the scope of what we claim.

Having described the invention, we claim:—

10. 1. The combination, in a gas stove, of spring influenced locking means for each cock that controls the passage of the gas to the burners, means concealing said locking means, and means for simultaneously releasing all of the locking means to permit of the turning of one or of all of the cocks.

2. In a gas stove having cocks controlling the gas passage to the burners and stop pins limiting the turning of said cocks, of locking means for each cock, comprising a shank guided for vertical movement along the side of each cock and held from turning thereon, a cam head which is arcuate in plan and which terminates in a shoulder on each of 25 the shanks, said shoulders designed to contact with the stop pins for preventing the turning of the cocks, a bar connecting all of the shanks, and an operating handle on the bar whereby the latter may be depressed to influence all of the shanks to bring the cam heads thereof out of engagement with the pins on the cocks.

3. In a gas stove having cocks controlling the gas passage to the burners and stop pins limiting the turning of said cocks, of locking means for each cock, comprising a shank guided for vertical movement along the side of each cock and held from turning thereon, a cam head which is arcuate in plan and 35 which terminates in a shoulder on each of the shanks, said shoulders designed to contact with the stop pins for preventing the turning of the cocks, a bar connecting all of

the shanks, and an operating handle on the bar whereby the latter may be depressed to 45 influence all of the shanks to bring the cam heads thereof out of engagement with the pins on the cocks, and spring means influencing the bar in an opposite direction.

4. The combination, in a burner having a 50 cock controlling the fuel supply therefor, and the core of the cock having a pin limiting the turning thereof; of a spring influenced member along the side of the cock held against turning therealong, a cam head 55 on said member having an inner shoulder which normally engages the pin for holding the cock from turning, and means for moving the member to allow the turning of the cock in one direction.

5. In a gas stove having gas cocks controlling the passage to the burners, stop pins limiting the turning of said cocks, a pilot, a gas conducting pipe therefor and a spring influenced valve sustaining the passage 65 partly open; of locking means for each cock, comprising a shank guided for vertical but held against turning movement on the side of each cock, a cam head which is arcuate in plan and which terminates in a shoulder on 70 each shank and the shoulders of the cam heads designed to contact with the stop pins for preventing the turning of the cocks, a bar connecting all of the shanks, an operating handle for the bar straddling the gas 75 pipe for the pilot and disposed for contact with the valve in the said pipe, and said handle when depressed designed to fully open the last mentioned valves and to move all of the shanks to bring the shoulders of 80 their cam heads out of engagement with the pins of the cocks.

In testimony whereof we affix our signatures.

MAX J. SINDLER.
JOSEPH SCHLOSS.
